LUBRICATING MEANS FOR SEWING
MACHINE LOOP-TAKERSWalter Myers, Bridgeport, Conn., assignor to The
Singer Manufacturing Company, Elizabeth,
N. J., a corporation of New Jersey

Application November 12, 1937, Serial No. 174,137

12 Claims. (Cl. 112—256)

This invention relates to improvements in means for lubricating the thread-case raceway of sewing machine loop-takers and more particularly the thread-case raceway of loop-takers of the horizontal-axis rotary hook type.

The present invention has for its primary objects to provide simple and efficient means for supplying lubricant to thread-case raceways of rotary loop-takers and to bearings of the loop-taker actuating shafts. Other objects of the invention will be apparent from the following description and claims.

The invention consists in the lubricating means hereinafter described in connection with the accompanying drawing which illustrates a preferred embodiment of the invention, and in which:

Fig. 1 represents a vertical section of a portion of the bed-plate of a sewing machine containing the improvement, the needle and the lower portion of the needle-bar being shown in elevation. Fig. 2 represents a cross-section on substantially the line 2—2 of Fig. 1.

The sewing machine illustrated in the drawing has a work-supporting bed-plate 1 provided with a throat-plate 2 having the usual aperture 3 for the vertically reciprocating needle 4 carried by the needle-bar 5.

Cooperating with the needle 4, below the throat-plate 2, in the formation of lock-stitches, is a rotary loop-taker 6 which, in the present instance, is of the horizontal-axis rotary-hook type and performs two rotations for each reciprocation of the needle. The loop-taker 6 has a cup-shaped body internally provided with an annular raceway 7. Journaled in the raceway 7 is the peripheral bearing rib 8 of a thread-case 9, said thread-case being restrained against rotation with the loop-taker by a stationary stop-finger 10.

The loop-taker 6 has a hub 11 of which the axial aperture is closed at the inner face of the loop-taker body by a plate 12. The loop-taker body has a radially extending duct 13 connected at its outer end with a transverse, wick-filled duct 14 opening into the raceway 7. The duct 13 is illustrated, in the drawing also as wick-filled, but this wicking may be omitted.

The hub 11 of the loop-taker 6 is secured by a screw 15 upon one end of a horizontally disposed loop-taker shaft 16, the end of said shaft within the hub 11 being preferably spaced from the plate 12 to provide therebetween an annular recess 17 in which the inner end of the radial duct 13 terminates. The shaft 16 is rotatably journaled in a

horizontal aperture 18 of a bearing-bushing 19, secured by a screw 20 for endwise adjustment in an aperture 21 provided in a casing or supporting block 22 depending from the bed-plate 1.

The loop-taker hub 11 abuts one end of the bearing-bushing 19 and extends through a clearance-aperture 23 of a guard-plate 24 having an annular flange 25 secured by screws 26 to the end-face of the supporting block 22, a sealing gasket 27 being preferably interposed between the flange 25 and the block 22. The flanged guard-plate 24 provides a cavity 28 collecting oil seeping from the adjacent end of the shaft-bearing aperture 18 of the bearing-bushing 19, which oil is centrifugally thrown off by the end of the loop-taker hub 11. The oil-collecting cavity 28 is constantly drained through a groove 29 in the outer face of and extending lengthwise of the bushing 19 from the bottom of said cavity 28.

The casing or supporting block 22 is provided with a downwardly open cavity 30, closed by a plate 31 removably secured to the bottom of said block by screws 32, a gasket 33 being preferably employed to seal the joint. One end of the bearing-bushing 19 extends into the cavity 30, and the end of the loop-taker shaft 16 within said cavity carries a driven spur-gear 34 which bears against said end of the bushing. Meshing with the spur-gear 34 is a driving spur-gear 35 secured by a screw 36 upon one end of a loop-taker actuating shaft 37. The shaft 37 is journaled in a bearing-bushing 38 secured by a screw 39 for endwise adjustment in a horizontal aperture 40, provided in the wall of the block 22 at the side of the cavity 30 opposite to the wall which supports the bushing 19. In the present case, the spur-gears are proportioned so that the loop-taker shaft rotates twice for each rotation of the shaft 37, the latter performing one rotation for each complete reciprocation of the needle and being actuated in any usual or suitable manner.

It will be understood from the foregoing description that the gears 34 and 35 are housed in the cavity 30 of the block 22. The cavity 30 also serves as a lubricant chamber, the lubricant being supplied thereto through an aperture 41 in the bed-plate 1 and opening into said cavity, said aperture 41 being normally closed by a screw-plug 42. The depth of the lubricant in the cavity 30 is preferably limited by providing a side wall 50 of said cavity with an aperture 43 normally closed by a screw-plug 44, said aperture 43 being so located that the teeth of the driving spur-gear 35 dip into the lubricant.

The loop-taker shaft 16 has a longitudinal bore 55

45 extending throughout the length of the shaft, the end of said shaft carrying the loop-taker bearing counter-bored to provide an annular shaft-recess 46 adjacent to and opening into the loop-taker recess 17. Suspended lengthwise in the shaft-bore 45 so as to be spaced from the shaft 16 is a stationary oil-conduit in the form of a tube 47, of which one end terminates in the loop-taker recess 17 and the other end is suitably secured in a 5 horizontal aperture 48 provided in a supporting plug 49. The plug 49 is adjustably secured by a screw 50 in an aperture 51 of the block 22, in alignment with the bearing-bushing aperture 21 of said block, said plug extending into the block-cavity 30 and having its inner end closely adjacent to the spur-gear 34 as well as spaced from the upper wall of said cavity 30. The described inner end of the supporting-plug 49 is provided with a substantially vertical oil-collecting pocket 52, said 10 pocket having its open upper end exposed within the cavity 30 and its lower end connected with the tube 47.

During the operation of the machine, the rotating gears 34, 35 serve as lubricant-impelling means, and splash the lubricant against the upper wall of the cavity 30, a portion of said lubricant being collected by the pocket 52 and being delivered by the stationary tube 47 into the loop-taker recess 17 for supplying lubricant to the connected wick-filled ducts 13, 14 of the loop-taker. Excess lubricant delivered by the tube 47 will drain back through the shaft-bore 45, outside the tube 47, and into the block-cavity 30. As the loop-taker recess 17 is slightly larger in diameter than the shaft-recess 46, and as the shaft-recess 46 is itself slightly larger diametrically than the shaft-bore 45, a small quantity of lubricant remains in said recesses even after the machine is stopped. This has the advantage that lubricant 25 is immediately supplied to the radial bore 13 of the loop-taker upon starting the machine. The radial bore 13 is so located in the loop-taker body that said bore is disposed above the loop-taker recess 17 in the usual stopping position of the machine 30 with the needle in raised position, so that no lubricant is supplied to said radial bore when the machine is idle.

Inasmuch as oil is splashed against the top wall of the cavity 30 at even moderate speeds of operation of the machine, oil is collected in the pocket 52 at any speeds actually requiring lubrication of the loop-taker raceway. The oil is delivered without pressure by the tube 47 to the loop-taker recess 17 and, while it will therefore be understood that the supply is substantially constant, the quantity of oil conducted to the raceway 17 varies with the centrifugal oil-feeding action through the radial bore 13 of the loop-taker at different speeds of operation of the machine. 40 This action is permitted because of the fact that an excess of oil is delivered by the tube 47, as already described.

The end-portion of the bearing-bushing 19 which extends into the cavity 30 is provided with an oil-duct 53 having its open outer end directed toward the upper wall of the cavity 30 and its inner end terminating in a groove 54 in and extending lengthwise of the shaft-bearing face of the bushing 19, said groove preferably terminating short of the opposite ends of the bushing. As previously explained, any oil which may seep from the bushing at the loop-taker end of the shaft 16 is collected in the cavity 28 and is returned through the drainage groove 29 to the 45 block-cavity 30.

The actuating shaft bushing 38 is likewise provided with an oil-collecting duct 55 which opens into a groove 56 in and extending lengthwise of the shaft-bearing face of said bushing 38, said groove preferably terminating short of the opposite ends of the bushing. It will therefore be understood that the bearings for the shafts 16 and 37, carried by the block 22 are automatically lubricated upon operation of the machine. 5

Having thus set forth the nature of the invention, what I claim herein is:—

1. In a sewing machine, a rotary loop-taker body having a thread-carrier raceway and provided with a recess having lubricant-conducting connections with said raceway, a stationary lubricant-conduit terminating in said recess substantially axially of said loop-taker body, and means for supplying lubricant to said conduit. 10

2. In a sewing machine, a rotary loop-taker body having a thread-carrier raceway and provided centrally of said body with a recess having lubricant-conducting connections with said raceway, a stationary lubricant-conduit coaxial with said body and terminating in said recess, and means for supplying lubricant to said conduit. 20

3. In a sewing machine, a rotary loop-taker having a thread-carrier raceway, a rotary shaft carrying said loop-taker and provided with a longitudinal bore having lubricant-conducting connections with said raceway, a stationary tubular conduit extending lengthwise of said shaft bore within and in spaced relation to said shaft, and means effective during the operation of the machine for supplying lubricant to said conduit. 25

4. In a sewing machine, a rotary loop-taker body having a thread-carrier raceway and radially-extending means for conducting lubricant to said raceway, a rotary loop-taker shaft having a longitudinal bore, a stationary lubricant-conduit disposed within the bore of said shaft and having one end terminating adjacent to said radially-extending means, and means effective during the operation of the machine for supplying lubricant to said conduit. 35

5. In a sewing machine, a rotary loop-taker body having a thread-carrier raceway and lubricant-conducting means connected with said raceway, a rotary shaft carrying said loop-taker body and provided with a longitudinal bore, a stationary conduit disposed lengthwise in the bore of 50 said shaft, said conduit having one end terminating adjacent to said lubricant-conducting means of the loop-taker body, and means effective during the operation of the machine for supplying lubricant to said conduit. 45

6. In a sewing machine, a rotary loop-taker body having a thread-carrier raceway, a stationary lubricant-conduit coaxial with said raceway and extending into said body, means effective during the operation of the machine for supplying 60 lubricant to said conduit, and means for directing to said raceway lubricant delivered by said conduit within said body. 55

7. In a sewing machine, a rotary shaft, a loop-taker carried by one end of said shaft and having a thread-carrier raceway, said shaft having a longitudinal bore extending from the end of said shaft opposite to the loop-taker end thereof and having lubricant-conducting connections with said raceway, a stationary tubular conduit extending into the bore of and spaced from said shaft, a conduit-supporting member having a lubricant-collecting pocket open to said conduit, and means effective during the operation of the machine for supplying lubricant to said pocket. 65

8. In a sewing machine, a rotary loop-taker body having a thread-carrier raceway and provided centrally of said body with a recess having lubricant-conducting connections with said raceway, a rotary shaft carrying said loop-taker and having a longitudinal bore, a stationary lubricant-conduit extending lengthwise through said shaft-bore and having one end terminating in said recess, a member supporting the other end of said conduit and provided with a lubricant-collecting pocket open to said conduit, and means effective during the operation of the machine for supplying lubricant to said pocket.
9. In a sewing machine, a rotary loop-taker body having a thread-carrier raceway and provided with a recess having lubricant-conducting connections with said raceway, a casing having a lubricant-supply chamber, means effective during the operation of the machine for delivering lubricant to said recess from said chamber, and means for draining into said chamber excess lubricant delivered to said recess.
10. In a sewing machine, a rotary loop-taker body having a thread-carrier raceway and provided with a recess having lubricant-conducting connections with said raceway, a rotary loop-taker carrying shaft having a longitudinal bore terminating at one end in said recess, a stationary lubricant-conduit disposed lengthwise within said shaft to provide a recess-draining channel in the bore of said shaft exteriorly of said conduit, said conduit having one end terminating in said recess, and means connected to the other end of said conduit for supplying lubricant thereto.
11. In a sewing machine, a rotary shaft having a longitudinal bore, a centrally recessed loop-taker body secured upon one end of said shaft and provided with a thread-case raceway having lubricant-conducting connections with the central recess of said body, said shaft-bore having a counter-bore connection with said recess, a lubricant-conduit disposed in the bore of said shaft and having one end terminating in said recess, and means connected to the other end of said conduit for supplying lubricant thereto.
12. A sewing machine having a cloth-plate, a supporting block depending from said cloth-plate and provided with a lubricant-supply chamber, lubricant-impelling means within said chamber, a horizontally apertured bearing-bushing secured in said supporting block and having a lubricant-collecting duct within said chamber, a rotary shaft journaled in said bearing-bushing, a loop-taker secured upon one end of said shaft and having a thread-case raceway, a lubricant-collecting pocket within said chamber, means for directing lubricant collected by said pocket to said raceway, means for directing lubricant collected by said duct lengthwise of the shaft-bearing face of said bushing, a guard-plate providing an oil-collecting cavity at the loop-taker end of said bushing, and means for draining lubricant from said guard-plate cavity into said chamber.

WALTER MYERS.
